UNITED STATES PATENT OFFICE.

GUY W. SEASHOLE, OF CLIFTON FORGE, VIRGINIA, ASSIGNOR TO J. G. FRY, OF CLIFTON FORGE, VIRGINIA.

HYDRAULIC JACK.

1,054,871.

Specification of Letters Patent.

Patented Mar. 4, 1913.

Application filed July 5, 1912. Serial No. 707,942.

To all whom it may concern:

Be it known that I, GUY W. SEASHOLE, a citizen of the United States, residing at Clifton Forge, in the county of Alleghany and State of Virginia, have invented new and useful Improvements in Hydraulic Jacks, of which the following is a specification.

My invention relates to body lifters and conveyers.

10 The object of my invention is to produce a portable device for lifting and conveying the bodies of sick or injured persons or of those from which life is extinct.

15 A further object thereof is to produce a movable platform on which is erected an hydraulic or pneumatically operated lifting jack adapted to elevate and transport the body of a person.

20 A still further object of my invention is to provide an hydraulic or pneumatic lifting pump upon said platform suitably coupled with an elevating rod adapted to elevate same and hold it at the desired elevation for the operation of the body handling means, more fully described in my pending application for patent, Serial Number 663,241, and a still further object thereof is to provide a more simple, cheap and efficient 25 portable body lifter than has heretofore been produced.

20 To these ends, my invention includes the combinations and arrangement of component parts to be hereinafter described, and 35 more particularly pointed out in the claim.

30 In the accompanying drawings in which like reference characters indicate similar parts, Figure 1 is a perspective view of my invention, and Fig. 2 is a vertical sectional view of the same.

Referring now to the drawings, 1 indicates the base of my elevator and carrier, which preferably comprises a rectangular plate which is mounted at its corners on 45 wheels or casters 2, preferably carried in ball bearing stems 3 to facilitate the travel thereof. Upon the upper face of said plate 1 and cast integrally therewith I provide at predetermined positions the internally 50 threaded upwardly extending annular flanges or collars 4, 5, and 6, into which are screwed the vertical cylindrical reservoir 7, the elevating cylinder 8 and the pump cylinder 10, respectively, the latter being with-

in the first mentioned, and at the base of the 55 elevating cylinder is provided a suitable check valve 11, hereinafter described. The outlet for said pump 10, within the reservoir 7, and the elevating cylinder 8, are connected by a channel 12 beneath the base 60 plate 1 to permit liquid or air to pass from the pump to the elevating cylinder to raise the piston and crane as more particularly described hereinafter.

65 The elevating cylinder 8, as before stated, being screw threaded into the flange 4 on the base 1 communicates with the pump 10 at its base through the channel 12, and is braced in its upright position to the reservoir cylinder 7 by the stay rods 13. At the 70 base of said cylinder 8, and integrally cast in the base 1, I provide a seat 15 for the ball valve 11 at the mouth of the channel 12, to permit the intake of liquid or air from the pump, but to prevent its return there- 75 through, which is otherwise provided for as hereinafter described.

Within the elevating cylinder 8 is carried the piston rod 14, at the lower end of which is provided the double headed piston 16 80 fitting snugly thereon adapted to be raised by the pressure from the pump 10. The opposite end of the piston rod extends beyond the top of the cylinder, and terminates in the curved crane 17 and eyelet 18 upon 85 which is adjustably swiveled the beam 19.

The top of the elevating cylinder is closed with a nut 20 which is provided with an aperture to accommodate the piston rod and form an upper bearing therefor. 90

Within the reservoir cylinder 7, is provided the pump cylinder 10 of less diameter and height than the reservoir. Said inner cylinder is provided with the pumping piston rod 21 and piston 22 on the lower end 95 thereof, adapted to force the liquid or air through the channel beneath the base 1 into the elevating cylinder 8. The outer or upper end of the rod 21 extends beyond the top of the cylinder 7 and is coupled with the pumping lever 23 hereinafter described. 100

Adjacent to the base of the pump cylinder 10, I provide an opening and conical valve 24 and beveled seat therefor in the wall thereof adapted to permit the intake of 105 liquid or air from the reservoir on the upstroke of the piston and to automatically close on the downward pressure thereof.

Said valve is held against displacement by the cage 24¹ secured upon the inner face of the cylinder.

The upper end of the reservoir cylinder 5 is closed by a cap through an aperture in which the piston rod projects.

The pumping lever 23, before mentioned, is fulcrumed at one end to the pivoted rod 25, and at the opposite end is forked or bifurcated to secure the handle grip 25¹ between the members thereof. Intermediate of the ends of said lever, a plurality of orifices 25^a are provided in which the outer end of the pumping piston rod 21 is pivoted 15 to regulate the leverage, and it will be appreciated that the pivoted fulcrum will permit such adjustment and likewise retain the concentric position of the piston rod by shifting the position of the fulcrum in the 20 upward and downward strokes of the pump.

I will now proceed to describe the means provided for lowering the elevating piston and crane, and the return of the liquid or air into the reservoir 7.

Intermediate of the elevating cylinder 8 and the reservoir 7, I provide a return pipe 26 which has a branch 26¹ at its lower end communicating with the elevating cylinder 8 beneath the piston 16, and at its top it is 30 provided with a branch 26^a leading into the reservoir 7 above the pump cylinder. Intermediate of said branches, I provide a valve 27 in the pipe 26 adapted to control the flow of liquid or air from the elevating 35 cylinder 8 to the reservoir 7. On the end of the valve stem 27¹, I provide an arm or crank 27^a which extends upwardly between the braces and between the reservoir and elevating cylinder where it is in convenient 40 reach of the operator.

It will be apparent that when the valve 27 is closed the operation of the pump will force the air or liquid through the channel beneath the base into the elevating cylinder

and raise the piston and rod therein, and 45 that when it is opened the liquid or air will flow backward through the branches and pipe 26, under the pressure of the weight of the lifting piston and rod, and return to the reservoir cylinder. For the purpose of 50 preventing the splash of the liquid contents on such return, I provide a deflector 28 at the top of the orifice through which the branch 26^a enters the reservoir.

As shown in the drawings, the pump fulcrum 25 may be swiveled on the upper end 55 of the return pipe 26.

Having thus described my invention, what I claim as new, and desire to be secured by Letters Patent, is—

The combination with a portable base, of a reservoir cylinder removably mounted thereon, of a pump cylinder of less diameter and height removably mounted on said base within said reservoir cylinder, a reciprocating piston in said pump cylinder, an inlet valve adjacent to the base of said pump cylinder, an elevating cylinder removably mounted on said base offset from said reservoir cylinder having a piston and crane 70 carried therein, a channel in said base connecting the bases of said pump cylinder and elevating cylinder, an automatic valve in said base within said elevating cylinder at the mouth of said channel, a return pipe 75 leading from the elevating cylinder beneath the piston therein to the reservoir cylinder above the pump cylinder therein, a valve in said return pipe intermediate its ends, and a pump lever pivotally fulcrumed at 80 one end on a rod pivoted on said return pipe and adjustably pivoted intermediate its ends to the piston rod of the pump, substantially as described.

GUY W. SEASHOLE.
